UNITED STATES PATENT OFFICE.

CHARLES R. BROWNING, OF MADRID, NEBRASKA.

NON-REFILLABLE BOTTLE.

1,113,953.

Specification of Letters Patent. Patented Oct. 20, 1914.

Application filed April 5, 1913. Serial No. 759,182.

To all whom it may concern:

Be it known that I, CHARLES R. BROWNING, a citizen of the United States, residing at Madrid, in the county of Perkins and State of Nebraska, have invented certain new and useful Improvements in Non-Refillable Bottles, of which the following is a specification.

This invention relates to bottle closures and has for its primary object, the provision of a vessel of this class with a neck attachment so constructed that when the bottle has been filled and the neck attachment applied, the said vessel may be emptied of its 10 contents but cannot be refilled or reused.

Another object of this invention is the provision of a valve and accessories therefor which are mounted on the interior of the bottle and aid in preventing the refilling of the bottle as well as in the dispensing of liquid which is contained therein, the said valve accessories being operated from the interior of the bottle for the dispensing of the liquid and so constructed and 20 arranged that the outflow of the same may be regulated.

With the foregoing and other objects in view, this invention consists in such novel features of construction, combination and 30 arrangement of parts as will be hereinafter more fully described, illustrated in the accompanying drawings and claimed.

In describing the invention in detail, reference will be had to the accompanying 35 drawings wherein like characters denote like or corresponding parts throughout the several views, and in which;

Figure 1, is a longitudinal sectional view through the improved non-refillable bottle; 40 Fig. 2, is a detail sectional view taken through the body of the bottle and at right angles to that shown in Fig. 1; Fig. 3 is a cross sectional view on the line 3—3 of Fig. 1; and, Fig. 4, is a sectional view on the 45 line 4—4 of Fig. 1.

In referring to the drawings by numeral, 1 designates the body portion of the bottle which is preferably flat or of that type commonly used in the dispensing of various 50 drugs or the like and which has the inlet or neck portion 2 formed integrally therewith and extending upwardly. The neck 2 of the bottle, is provided with an annular projection 3, near the upper end thereof, 55 which has a recess 4 therein, communicating with the recess in the interior of the

neck 2. After the body portion 1 of the bottle, has been filled with any desirable liquid, the stopper 4' of ordinary cork or similar material is inserted into the recess 60 in the neck portion 2 as is shown in Fig. 1. A second stopper 5, which is preferably made of glass is also inserted within a recess of the neck 2. The stopper 5 has an aperture 6 extending therethrough into which are mounted two members 7 and 8 and which have an expanding coiled spring 9 disposed between their inner ends. When the stopper 5 is inserted into the recess of the neck 2 until the members 7 and 8 are 70 directly opposite the recess 4 within the annular projection 3, the coil spring 9 will force the two members 7 and 8 outwardly causing them to seat themselves in the recess 4 thus preventing removal of the stoppers 4' and 5 from the bottle without the 75 breaking of the neck.

A tube 10 is formed integrally with the body portion 1 of the bottle, and extends longitudinally the full length thereof having a small opening 11 in its upper end at the point of connection between the same and where the bottle terminates into the neck portion 2. This opening 11 communicates with the recess in the interior of the 85 body portion 1 of the bottle and forms a means for allowing the liquid which is contained within the recess 12 of the body portion 1 of the bottle to enter the recess 13 in the interior of the tube 10.

A cork 14 which has an aperture 14' extending therethrough is slidably mounted within the tube 10 and has one end of a second tube 15 mounted therein, as is shown at 16. The aperture 14' in the cork 14 is 95 enlarged at its lower end as at 17 and forms a seat for the ball valve 18 which is mounted upon the upper end of the valve stem 19. The valve stem 19 is rigidly mounted in a plate 20 which is formed integrally with 100 the sides of the tube 15 and has a coil spring 21 mounted thereabout and controlled by a plate 22. The plate 20 is provided with a plurality of openings 23 therethrough which communicate with the recess 24 of the lower 105 section of the tube 15. The lower end of the tube 15 terminates in a solid block 25 which has a screw threaded aperture 26 therein. The screw threaded aperture 26 communicates with a second aperture or opening 27 110 which in turn communicates with the recess 24 in the lower portion of the tube 15. The

outer side 28 of the body portion 1 of the bottle, has a slot 29 formed therein which receives the outer end of the tube 30.

The tube 30 has external screw threads 5 upon its inner end which engage the internal screw threads upon the aperture 26 for rigidly and securely holding the tube 30 in place. A stopper 31 is mounted in the outer end of the tube 30 and forms a closure for 10 the same while the upper side of the tube, of the inner end thereof is provided with a slot 32 which communicates with the aperture 27, and completes the source of outlet for the liquid contained in the recess 12. 15 When it is desired to dispense the liquid contained in the recess 12 of the body portion 1 of the bottle, the latter is turned so that the liquid will pass through the opening 11 into the recess 13. The stopper 14 and the tube 15 are then forced upward by 20 means of the tube 30 which extends out of the bottle as is shown in Fig. 2 of the drawings and the liquid is forced downwardly through the aperture 14', passing the valve 25 18 into the opening 24 in the lower portion of the tube 15 and out through the tube 30 by means of the opening 27 and slot 32 into any desirable container. By altering the size of the recess 13 or the space between 30 the two corks 4 and 14, the amount of liquid dispensed at each operation of the mechanism mounted within the tube 10 may be regulated as desired.

In practical fields certain minor features of construction, combination and arrangement of parts may necessitate alterations to which the patentee is entitled provided such alterations are comprehended within the scope of what is claimed. 35

I claim—

1. A bottle having a closed neck, a tube formed integrally with the body of said bottle, a second tube slidably mounted in said first tube, valve mechanism in said second tube, said first tube provided with an aperture communicating with the interior of said bottle, the body of said bottle provided with a slot, and a discharging vent passing through said slot and into said tubes for facilitating the dispensing of liquid contained in said bottle. 40

2. A bottle provided with a closed neck having a tube formed integrally therewith, said tube provided with an opening communicating with the interior of said bottle, a second tube slidably in said first tube having valve means therein, said first and second mentioned tubes provided with discharge vents to facilitate the dispensing of liquid contained in said bottle. 45

In testimony whereof I affix my signature in presence of two witnesses.

CHARLES R. BROWNING.
